R. D. SCHNOOR

RADIATOR CAP LATCHING DEVICE

Filed Feb. 13, 1925.

Fig. 2.

Fig. 1.

Inventor:

Raymond D. Schnoor

By Munday, Clark & Carpenter, Attn:

UNITED STATES PATENT OFFICE.

RAYMOND D. SCHNOOR, OF MAYWOOD, ILLINOIS, ASSIGNOR, BY MESNE ASSIGNMENTS,
TO THE NORLIPP COMPANY, OF CHICAGO, ILLINOIS, A CORPORATION OF ILLINOIS.

RADIATOR-CAP-LATCHING DEVICE.

Application filed February 18, 1925. Serial No. 3,895.

My present invention relates in general to radiator caps, and more particularly to that type of cap having a hinged filling opening and adapted to be non-removably 5 secured to the neck of a radiator.

The principal object of the invention is to provide a radiator cap that will be symmetrical in design and that will have no sharp or frail projections that may catch 10 and tear fabrics, or that may be accidentally broken away.

Another object is to provide such a device that will not be opened accidentally and that may be readily opened if desired by a 15 slight pressure of the finger, that will be efficient, economically produced and readily assembled.

Numerous other objects and advantages 20 will be apparent as the invention is better understood from the following description, which, taken in connection with the accompanying drawings, discloses a preferred embodiment thereof.

Referring to the drawings:

Fig. 1 is an elevation of a device embodying my invention with parts broken away.

Fig. 2 is a plan view of the device.

While it is possible to use the device with 30 various radiator caps and the like, to illustrate my invention, I have shown a body 11 having a filling opening 12 provided with a flexible gasket 20 and positioned over an adapter 13 by which it may be non-removably secured to the neck of a radiator 14. The body 11 is provided at its opposite sides 35 with outwardly extending arms 15 which may be to facilitate the turning of the cap or merely for ornamentation. A closure member 16 having an opening 17 therein into which the neck of a condition indicator or motor meter 18 may be secured is secured to the body by means of a hinge pin 19 extending through the lug 21 of the closure member and the lugs 22 extending upwardly 40 from the body 11.

A latch 23 is pivotally secured in the closure member 16 by a pin 24 having bearings in the arms 25 formed integral with the closure member 16. A spring 26 normally tends to rotate the latch in a counter-clockwise direction and is secured to a connecting web 27 between the arms 25. An arm 40 on the latch 23 engages the end of the web 27 to limit the movement of the latch. An arm 28 of the latch is cut away 45

at 29 to form a hook and the end of the arm is preferably chamfered or rounded as at 31. A pocket is provided in the body 11, preferably at the base of one of the arms 15, and a plate 33 being slightly greater in 60 width than the pocket 32 to provide a drive fit is positioned in said pocket adjacent the outer wall 34. This plate is preferably of a hard material having wearing qualities 65 and is bent at right angles at 35 to provide a flange. A pin 36 having an enlarged diameter providing a button 37 and a groove 38 is positioned in an arm 15 of the body 11. A split washer 39 is positioned in the groove 38 and moves with the pin 36. A spring 41 positioned over the pin 36 and in a bearing 42 normally tends to hold the pin 36 in the position shown (Fig. 1) with the washer 39 engaging the plate 33.

The cap may be opened for filling the radiator or the like by a slight pressure on the button 37, which it will be noted moves the washer 39 to the left (Fig. 1) to disengage the latch 23 from the flange of the plate 33 which entirely releases a side of the closure member, the gasket 20 being slightly compressed upon closing raises the closure member slightly and permits the swinging thereof about the hinge pin 19. To secure the cap in closed position, it is only necessary to close the cap, as it will be noted that the chamfered end 31 of the arm 28 of the latch striking the top of the plate 33 moves the latch in a clockwise direction against the force of the spring 26 until the hook passes the end of the flange, at which time the hook will be actuated by the spring 26 to engage behind the flange. 75 80 85 90 95

It is thought that the invention and many of its attendant advantages will be understood from the foregoing description and it will be apparent that various changes may be made in the form, construction arrangement of the parts without departing from the spirit and scope of the invention or sacrificing all of its material advantages, the form hereinbefore described being merely a preferred embodiment thereof. 100

I claim:

1. A latching device for use with a radiator cap having a body provided with a filling opening and a portion extending outwardly therefrom, and a closure for said opening secured to said body, said device comprising a latch member pivoted in said 105 110

closure and adapted to engage the body to secure said cover in closed position, and means including a slidable finger-operated member for disengaging said latch member, said means being mounted in the outwardly extending portion of said body.

2. A latching device for use with a radiator cap having a body provided with a filling opening and an arm extending outwardly therefrom, and a closure for said opening secured to said body, said device comprising a latch member pivoted in said closure and adapted to engage the body to secure said cover in closed position, and a two diameter yieldable pin slidably mounted in the outwardly extending arm of said body for disengaging said latch member.

3. A latching device for use with a radiator cap having a body attachable to the filler neck of a radiator and having laterally extending arms whereby said body may be rotated, and a cover hingedly secured to said body, said device comprising cooperating latching elements carried respectively by said cover and body, means for normally holding said latching elements in engagement, and means for disengaging said elements to permit opening of the cover, said last-mentioned means comprising a slidable member mounted within one of said arms, and a spring for holding said member normally in outer position, said member having a thumb portion projecting from the end of said arm and a portion engageable with one of said latching elements whereby the latter may be moved out of engagement with the other element when said thumb portion is pressed.

4. A latching device for use with a radiator cap having a body attachable to the filler neck of a radiator and having laterally extending arms whereby said body may be rotated, and a cover hingedly secured to said body, said device comprising cooperating latching elements carried respectively by said cover and body, means for normally holding said latching elements in engagement, and means for disengaging said elements to permit opening of the cover, said last-mentioned means comprising a slidable member mounted within one of said arms and a spring for holding said member normally in outer position, said member having a thumb portion projecting from the end of said arm and a portion en-

gageable with one of said latching elements whereby the latter may be moved out of engagement with the other element when said thumb portion is pressed, the engageable portions of said latching elements being inaccessibly disposed in an interior recess in said body.

5. A latching device for use with a radiator cap having a body attachable to the filler neck of a radiator and having laterally extending arms whereby said body may be rotated, and a cover hingedly secured to said body, said device comprising cooperating latching elements carried respectively by said cover and body, means for normally holding said latching elements in engagement, and means for disengaging said elements to permit opening of the cover, said last-mentioned means comprising a slidable member mounted within one of said arms and a spring for holding said member normally in outer position, said member having a thumb portion projecting from the end of said arms and a portion engageable with one of said latching elements whereby the latter may be moved out of engagement with the other element when said thumb portion is pressed, the engageable portions of said latching elements and the actuating portion of said slidable members being inaccessibly disposed in an interior recess in said body.

6. A latching device for use with a radiator cap having a body attachable to the filler neck of a radiator and having laterally extending arms whereby said body may be rotated, and a cover hingedly secured to said body, said device comprising a latching member pivotally carried by said cover, a cooperating fixed latching element in said body, the latter having a recess into which said pivoted latching member extends, a spring secured to the cover and acting upon said pivoted member to hold the same normally in engagement with said fixed latching element, a slidable member carried in one of said arms and having a head portion adapted to act upon said pivoted member when pressed inwardly, and a thumb portion protruding from the end of the arm, and means for holding said slidable member normally in position permitting engagement of the latch.

RAYMOND D. SCHNOOR.
